UNITED STATES PATENT OFFICE.

THOMAS E. TEEGARDEN, OF CHICAGO, ILLINOIS.

AMALGAMATING APPARATUS.

SPECIFICATION forming part of Letters Patent No. 586,324, dated July 13, 1897.

Application filed October 8, 1896. Serial No. 608,212. (No model.)

To all whom it may concern:

Be it known that I, THOMAS E. TEEGARDEN, a citizen of the United States, residing at Chicago, in the county of Cook and State of Illinois, have invented a new and useful Improvement in Amalgamating Apparatus, of which the following is a specification.

My invention relates to an improvement in the class of apparatus for separating precious metals from their ores by amalgamation in which the amalgamating pan or pans (also termed the "copper" or "coppers") are supported on a vertically-disposed or upright shaft stepped at one end—that is, held either above or below its center to adapt it to be swung without rotation upon its longitudinal axis, upon a pivot, as it were, to impart to the pan or pans a gyratory motion of a nature closely resembling the well-known motion employed in panning by hand.

The object of my invention is to afford an improvement in the class of amalgamating apparatus referred to, and this more especially in the particulars of cheapness of construction, economy of driving power, motion of the amalgamating pan or pans, and the feed to the latter.

Referring to the accompanying drawings, Figure 1 shows my improved apparatus by a view in sectional elevation, partly broken; Fig. 2, a section taken at the line 2 on Fig. 1 and viewed in the direction of the arrow; and Fig. 3 a view like that presented by Fig. 1, but showing the arrangement of my improved apparatus with a single amalgamating-pan instead of a series of such pans.

A is a shaft pivotally supported at one end in a suitable step B. In Fig. 1 the shaft is shown to be supported by suspension from its upper end, which is preferred, while in Fig. 3 it is shown to be supported at its lower end. The construction of the step B illustrated comprises a bed-plate *r*, provided with a pair of outward-extending perforated ears *r'*, in which is journaled a rock-shaft *q*, having outward-extending perforated ears *q'* at right angles to the ears *r'*, and in each is pivotally supported a socket *p* to receive the end of the shaft. The opposite end of the shaft

A is provided with suitable eccentric driving mechanism, the details of which, as illustrated in Fig. 1, are so well known that they

need not herein be more definitely described. D denotes the driving mechanism geared to the eccentric mechanism C and adapted to be connected with any suitable driving power.

E is the feed-pan, preferably of the flaring form illustrated and supported centrally upon the shaft A, the feed-pan containing a screen *o*, for a purpose hereinafter described. I prefer to support the pan E on the shaft, as by the means shown, involving a flaring sleeve *n*, which closely fits near its upper end about the shaft and is propped at its lower end by means of an adjustable collar *m*, and through the sleeve near its lower end are inserted set-screws *l* to bear at their inner ends against the surface of the shaft, whereby loosening one or more of the set-screws and tightening the others enables the feed-pan to be tilted to a desired limited degree by tilting the sleeve upon which the feed-pan seats in the manner illustrated. From the base of the pan E there extend the discharge-spouts E'.

In Fig. 1 I show a number of amalgamating pans or plates F, supported below the feed-pan E, to radiate from the shaft A, as from a common center, on a frame F', seated on a flaring sleeve *n'*, surrounding the shaft in the manner described of the sleeve *n*, and, like the latter, propped at its base by a collar *m'* and provided with set-screws *l'* for its adjustment in the manner of adjusting the sleeve *n*. The form of amalgamating-pan which I prefer to employ is that illustrated, involving a copper dish-shaped base *k*, provided with a discharge-spout *k'* and an undulated copper top plate *i* of lesser diameter than the base *k* to fit within the latter and leave a space at *x* about its edge, at which it is supported at intervals from the base by narrow clips *t*, and about the upper side of the plate *i*, near its edge, there extends a flange *i'*, tending to confine the pulp against too ready running off.

In Fig. 3, wherein only one of the amalgamating-pans F is shown, it is supported at its base *k* by seating directly on the sleeve *n'* concentrically with the shaft, and two discharge-spouts *k'* are shown to be provided in the base.

In each construction the amalgamating-pan in the one and the amalgamating-pans in the other are within a tailing-pit G, seated, like the single pan F, on the sleeve *n'* and having

a discharge-spout *h*, the form of the tailing-pit being preferably that of a funnel, as shown.

The operation is as follows: The ore-pulp is supplied from a suitably-located pulp-tank 5 (not shown) through a feed-spout *H* to the pan *E* (which may also be used as an amalgamating-pan) while the shaft *A* is being actuated by driving the eccentric mechanism *C*, which swings the shaft on its pivotal axis 10 through a circuitous path. This motion of the shaft gyrates the pan *E* and accordingly agitates its pulp contents, which after passing through the screen discharge through the spouts *E'* upon the pan or pans *F*. As will 15 be seen, the feed-spouts lead to the centers of the pans *F*, from which the material is thus distributed evenly and regularly over the surfaces of the mercury-covered plates *i*, and owing to the construction, whereby the 20 center of motion and center of the pans always remain the same, there is no variation in the points of discharge from the feed-pan with relation to the amalgamating pan or pans. The material passes from the top amalgamating-plate *i* over the edge of the latter into the dish-shaped base *k*, which should 25 contain mercury, and the tailings discharge into the pit *G*, whence they escape through the discharge-spout *h*.

30 Whenever it is desirable, as it sometimes is, to adjust the feed-pan *E* or a pan *F* for the purpose of leveling the same upon its center, so as to tilt it more or less with relation to the shaft, this may be done by accordingly 35 adjusting the sleeves *n* or *n'* by properly manipulating the set-screws *l*. There is no material difference in the result of the operation of the apparatus whether the pivotal support for the shaft be at its upper or at its 40 lower end.

What I claim as new, and desire to secure by Letters Patent, is—

1. In an amalgamating apparatus, the combination of a shaft supported in upright position at one end to be gyrated from its opposite end through a circuitous path about the 45

center of its support, means for gyrating the shaft, and one or more amalgamating-plates supported on said shaft and tiltingly adjustable thereon with relation to the shaft, substantially as and for the purpose set forth. 50

2. In an amalgamating apparatus, the combination of a shaft supported in upright position at one end to be gyrated from its opposite end through a circuitous path about the 55 center of its support, means for gyrating the shaft, a sleeve surrounding said shaft and adjustable thereon by tilting the sleeve with relation to the shaft, one or more amalgamating-plates supported on said sleeve, said shaft 60 affording the center of motion for the plate or plates, and a feed-pan supported on the shaft above, and discharging upon said plate or plates, substantially as and for the purpose set forth. 65

3. In an amalgamating apparatus, the combination of a shaft supported in upright position at one end to be gyrated from its opposite end through a circuitous path about the 70 center of its support, means for gyrating the shaft, a downwardly-flaring sleeve supported on the shaft and provided with means for adjusting it, and one or more amalgamating-plates supported on said sleeve, substantially as and for the purpose set forth. 75

4. In an amalgamating apparatus, the combination of a shaft supported in upright position at one end to be gyrated from its opposite end through a circuitous path about the 80 center of its support, means for gyrating the shaft, downwardly-flaring sleeves supported one above the other on the shaft and provided with means for adjusting them, one or more amalgamating-plates supported on the 85 lower sleeve and a feed-pan supported on the upper sleeve and discharging upon said plate or plates, substantially as and for the purpose set forth.

THOMAS E. TEEGARDEN.

In presence of—

J. H. LEE,
R. T. SPENCER.
